F. A. MACMURTRY.
DAMPER CONTROLLING MECHANISM.
APPLICATION FILED APR. 25, 1916.

1,291,980.

Patented Jan. 21, 1919.

THE NORRIS PETERS CO., PHOTO-LITHO., WASHINGTON, D. C.

UNITED STATES PATENT OFFICE.

FRIEND A. MACMURTRY, OF NORTH BENNINGTON, VERMONT.

DAMPER-CONTROLLING MECHANISM.

1,291,980.

Specification of Letters Patent. Patented Jan. 21, 1919.

Application filed April 25, 1916. Serial No. 93,356.

To all whom it may concern:

Be it known that I, FRIEND A. MACMURTRY, a citizen of the United States, and resident of North Bennington, county of Bennington, and State of Vermont, have invented certain new and useful Improvements in Damper-Controlling Mechanisms, of which the following is a specification.

My invention relates to mechanisms for automatically controlling the dampers commonly located in the smoke pipes or flues of heating furnaces or other apparatus and has for its object to provide a simple and efficient arrangement whereby said dampers may be properly operated in unison with any other means which may be included in the heating apparatus for the purpose of controlling the source of heat therein. My improvement will be fully described herein-after and the features of novelty will be pointed out in the appended claim.

In the accompanying drawings I have illustrated my invention in combination with a heating apparatus for incubators, it being understood that this is only an example used for illustrative purposes. In said drawings Figure 1 is an elevation, partly in section of an incubator and its heating apparatus with my improvement operatively combined therewith; Fig. 2 is a detail view, partly in section, of a specific example of my improvement; Fig. 3 is a view thereof looking at right angles to Fig. 2 and Fig. 4 is a section on the line 4—4 of Fig. 3.

In the drawings 5 represents a furnace which may be of any suitable construction adapted for the particular purpose in hand and which in the illustration is provided with a water-jacket 6 connected by means of the pipes 7 and 8 with the heating system which may also be of any well known type and located at any place or places where the heating effect thereof is desired. In the illustrated example I have shown the pipes 7 and 8 leading to a heating system located in the interior of an incubator 9 which is diagrammatically indicated in the drawings as the details of its construction form no part of the present invention. The furnace 5 as shown, is constructed with a top chamber 10 and further includes a hinged damper 11 whereby the admission of cold air to the chamber 10 is controlled, the latter communicating with the chimney by way of the stove-pipe 12. The chamber 10 is connected with the fire pot 13 of the furnace by means

of a passage 10^a with which a throttle or damper 14 co-operates to control the products of combustion from the fire pot 13. The means for operating the dampers 11 and 14 in the illustrated example comprises a receptacle 15 supported for instance at a distance above the furnace in any suitable manner and connected by means of a pipe 16 with the pipe 8 whereby heated water is conducted to and maintained in said receptacle 15. A piston or float 17 is fitted within said receptacle 15 so as to be slidable therein and carries a stem 18 operatively connected with a pivoted lever 19 which in turn is connected by means of a link 20 with the damper 11. The illustrated arrangement further includes a rod or the like 21 whereby the throttle 14 is also operatively connected with said stem 18 and thus with the piston or float 17. The parts so far described form no part of my present invention and have simply been utilized for the purposes of illustration, the details of construction and the operation of the parts being clearly set forth in Patent No. 692277 issued to Wilbur P. Hall on February 4, 1902.

My invention as shown in the illustrated example comprises a plate or member 22 having a curved or cam slot 23 formed therein, said plate being adjustably and detachably connected with the rod 21 in any suitable manner as by clamps 24. An arm 25 extending at an angle to and preferably forming part of a member 26 slotted at 27 extends through the slot 23, the member 26 being adjustably connected, for instance by means of nuts and bolts 28 passing through the slot 27, with the actuating member 29 of the smoke pipe damper 30 rotatably mounted in the pipe 12 as shown in Figs. 2 and 4. The member 29 may as shown, comprise the usual handle whereby such dampers are ordinarily operated manually or if desired said member may be specially constructed to meet the requirements of any special conditions. As shown in Fig. 2 guides 31 may in some cases be provided through which the rod 21 or its equivalent extends so as to be slidable relatively thereto, said guides 31 extending for instance from the pipe 12 at points above and below the damper 29.

It will be understood that the water in the jacket 6 is acted upon by the furnace fire and as the intensity of the fire changes, is successively increased and diminished in temperature and thus successively expands and

contracts, and communicates this effect, through the pipe 16 to the water in the receptacle 15 whereby the piston or float 17 will periodically rise and fall in the receptacle and the link 20 and rod 21 will be actuated to successively open and close the dampers 11 and 14. That is, as the float 17 rises the rod 21 will descend to close the damper 14 while the link 20 will ascend to open the damper 11 and vice versa, the mechanism whereby said float is operatively connected with the link 20 and rod 21 being constructed to produce these results as clearly shown and described in the Hall patent hereinbefore referred to. Thus as the fire in the furnace becomes hotter and the liquid in the jacket 6, pipe 16 and receptacle 15 is caused to expand, the damper 14 will be closed and the check draft damper 11 will be opened whereby the draft through the furnace will be reduced and at the same time air will pass into the chamber 10 and over the fire pot 13 through the open draft damper 11. This brings about a reduction in the intensity of the fire so that eventually the piston 17 will drop due to the contraction of the water in the receptacle 15 and the damper 14 will be opened while the draft damper will be closed so that the heating effect of the fire is again increased. As the rod 21 rises and falls as described the plate 22 or its equivalent will be carried along and through the coöperation of the slot 23 and arm 25 will bring about an operation of the flue damper 30. In other words the actuation of the flue damper 30 will correspond to the actuation of the damper 14 so that both of these dampers are concurrently fully closed or fully open or occupy corresponding intermediate positions.

I have found that attempted regulation of the source of heat without the coöperation of the flue damper does not produce entirely reliable results as it is obvious that, with a free passage in the smoke flue 12 and with the draft damper 11 open, the air rushing into the chamber 10 quickly becomes heated especially if drawn from a warm room and continues to act for a time at least as a draft tending to maintain the intensity of the fire in the furnace, with a consequent loss of heat from the fire and a waste of fuel. On the other hand if a manually operated damper is provided and the same is permitted to remain partly or fully closed for instance to offset the above mentioned objections, the fire does not become intensified quickly when the damper 14 is opened and the draft damper 11 is closed. This oftentimes results in an undesired and considerable drop in temperature at the place or places being heated.

These objections are entirely overcome with my improvement which by being operatively combined with the other regulating devices augments the action thereof and coöperates therewith to quickly check the fire when desired and to bring about a rapid intensification thereof at the proper time. My improvements thus provide for the desired regulation of temperature in an efficient and reliable manner and results in a saving of fuel without affecting the efficiency of the heating plant and at the same time securing a substantially even fire and a substantially constant degree of heat therefrom with a substantially constant temperature at the place or places being heated.

The device may be readily combined with existing constructions without requiring any material changes or additions either in or to the furnace regulating means if such is included in the plant or in the flue damper arrangement and structure, and is adjustable in all cases to produce the desired results. It will be obvious that the plate 22 with its slot 23 or equivalent devices may be operatively combined with elements other than the rod 21, this being determined by the character of the particular regulating devices and means for operating same which are included in the particular heating plant with which my improvement is to be combined. It will further be apparent that said improvement is not limited to use in connection with heating apparatus for incubators but may be efficiently combined with many other types of apparatus intended for heating places other than incubators.

Various changes in the specific form shown and described may be made within the scope of the claim without departing from the spirit of my invention.

I claim:

The combination of a furnace, a smoke flue connected therewith, automatically operating means for regulating said furnace, a damper rotatably mounted in said smoke flue and having an actuating member extended exteriorly thereof, a slotted member adjustably connected with said actuating member, an arm forming a continuation of said slotted member and extending at an angle thereto, a member adjustably connected with the regulating means and provided with a cam slot operatively combined with said arm and arranged to actuate the same whereby said damper is operated coincidentally with said regulating means.

In testimony whereof I have hereunto set my hand.

FRIEND A. MACMURTRY.
